LAP PIN

Robert J. Higginbotham, Charlotte, N. C.

Application August 15, 1950, Serial No. 179,434

1 Claim. (Cl. 242—55.1)

1
This invention relates to pickers of the type employed in textile mills and more particularly to a lap pin on which a lap roll is formed.

In devices of this nature the cotton lap is formed by the lap machines by winding a batt or layer of cotton upon a shaft, commonly denoted as a lap pin. After the roll is formed the lap pin is withdrawn and a lap stick inserted in its place to facilitate handling of the roll. Instead of forcing a lap stick into the roll after withdrawal of the lap pin, the lap pin has often-times been provided with a hollow shaft for housing the lap stick which is left in the roll as the pin is withdrawn; for further illustration of the latter, reference is made to the patents to Clayton, 355,508 and Wilson, 2,105,064. Although the embodiment of the present invention is described as a lap pin of the solid type, it is understood that the invention is not restricted to such construction but is intended to embrace a lap pin having a lap stick combined therewith of the general type shown in the patents mentioned.

In lapper pickers the batt is generally wound tightly on the lap pin, the pin having a shaft protruding from its ends which is carried by suitable gudgeons or bearings during the winding operation. After the winding is completed the pin is removed from the gudgeons and withdrawn from the batt. Due to the friction between the pin and the contacting portion of the tightly wound batt, withdrawal of the pin has proved to be a problem. One solution has been to provide a pin of substantially frusto-conical contour, the base of the cone being near the handle portion of the pin, i. e., the portion which is withdrawn first from the batt. Such configuration of the pin facilitates withdrawal as it permits expansion of the batt radially inwardly as the pin is withdrawn and offers less resistance than the conventional cylindrical pin. However, difficulties are encountered in winding a lap roll onto a frusto-conical pin so that the lap roll will be substantially cylindrical and even at its sides and, furthermore, the gudgeons supporting the shaft of the pin are frequently forced out of alignment and excessive wear is caused as a result of the uneven pressure at the ends of the pin.

Accordingly, it is an object of the present invention to provide a lap pin particularly constructed for easy withdrawal from the lap roll and possessing the advantages of the conventional cylindrical pin insofar as the winding process is concerned.

A further object of the invention is the provision of a lap pin constructed particularly to

2
facilitate both winding of the lap roll thereon and withdrawal of the lap pin from the roll.

Further objects of the invention will be apparent from the following description taken in conjunction with the accompanying drawings wherein:

Fig. 1 is a sectional view through a lap roll showing in elevation a lap pin constructed in accordance with the present invention;

Fig. 2, an enlarged elevation partially in section illustrating the details of construction of the lap pin;

Fig. 3, a section on the line 3—3 of Fig. 2; and
Fig. 4, a section on the line 4—4 of Fig. 2.

Referring to the drawings, a lap pin 10 is illustrated having a lap roll R wound thereabout in Fig. 1. The lap pin comprises a main body 11 having a shaft 12, 12' extending from either end of the body and a handle 13 connected to the shaft 12.

The main body 11 of the lap pin is of substantially cylindrical configuration and has a plurality of spaced grooves 14 separated by a plurality of lands 15, the grooves being relatively shallow at the end of the main body nearer the handle 13 as shown in Fig. 4 and gradually becoming deeper toward the other end of the main body, as shown in Fig. 3. It will be observed that the peripheral surfaces of the lands 15 increase in direct ratio to the decrease in the depth of the grooves 14 which separate the lands. Thus, the arcuate outer edge of each land as viewed in Fig. 3 is of a substantially sharper radius than the outer edge of said land as viewed in Fig. 4 and the lap roll will, of necessity, have only point contact with the lands at the inner extremity of the lap pin remote from the handle 13 and will contact a substantially greater peripheral portion of said lands adjacent the outer end of the pin. With the configuration thus described, each land is provided with an arcuate surface of continually increasing radius from the inner to the outer end of the lap pin, the radius at the outer end of each land approaching that of the lap pin per se. The surface of revolution generated by revolution of the tops of the lands 15 about the axis of the pin is a cylinder. Thus the lap roll may be wound evenly on the main body 11 without the disadvantages normally accompanying the use of a frusto-conical pin.

The surface of revolution generated by revolving the bottoms of the grooves about the axis of the pin is frusto-conical, and thus the advantages of the use of a frusto-conical pin are provided without the accompanying disadvantages.

In order to facilitate removal, the grooves are formed along the surface of the main body in a slight helix, the rotation being approximately one-half inch on the circumference in an axial length of approximately forty inches. This is not intended to be a critical ratio but is merely illustrative of the pitch of the helix in order that those skilled in the art may better understand the invention.

In operation the lap pin is placed in gudgeons carrying the shaft 12 and 12' and the lap roll is wound thereon. Then the pin and roll are removed from the gudgeons, and an operator, by grasping the handle 13 and twisting it slightly as he pulls, may remove the lap pin from the roll. Because of the increasing depth of the grooves toward the free end of the pin, the roll may expand radially inwardly as the pin is removed in a manner analogous to removing a frusto-conical member.

The invention is best carried out by providing the helix as described in order that twisting as well as axial force may facilitate its removal but my invention is intended to include the broader embodiment in its scope.

The embodiment of the invention described is thus a lap pin having a shaft extending from its ends and having a main body of substantially cylindrical configuration with grooves in its surface tapering in depth from one end thereof toward the other and, preferably being arranged helically about the axis of the pin.

It will be obvious to those skilled in the art that various changes may be made in the invention without departing from the spirit and scope thereof and therefore this invention is not limited by that which is shown in the drawings nor by that which is described in the specification, but only as set forth in the appended claim.

I claim:

A lap pin comprising an elongated main body of cylindrical cross section having grooves extending from the inner end to the outer end thereof, said grooves being formed along the surface of said body in a slight clockwise helical direction and decreasing in depth from the inner end to the outer end thereof, and lands between said grooves, each of said lands having an arcuate surface of continually increasing radius from the inner end to the outer end of said lap pin in direct ratio to the decrease in depths of said grooves, the radius at the outer end of each land approaching that of the lap pin to provide a peripheral surface of greater extent.
